TOY RAILROAD

William R. Schneider, Buffalo, N. Y.

Application December 7, 1936, Serial No. 114,527

6 Claims. (Cl. 104—63)

This invention relates to a toy railroad and has as its object the provision of a trackway having a new and novel configuration.

Among the objects of the present invention are the provision of a trackway for a toy railroad whose course is new and novel and has been found to be practical and pleasing to observe; the provision of a trackway which is continuous and endless in its extent and is at the same time free from grade crossings, thereby eliminating the necessity for switches, frogs, and the like; and the provision of a trackway which fulfills the foregoing objects and has sufficient variety in its tortuous pathway to avoid the usual monotony of devices of this class and at the same time provides a simple and practical construction.

In the drawing:

Fig. 1 is a plan view of my new toy railroad trackway;

Fig. 2 is a side elevation thereof;

Fig. 3 is a vertical cross sectional view along the line 3—3 of Fig. 1; and

Fig. 4 is a vertical cross sectional view along the line 4—4 of Fig. 1.

While various structural designs may be devised for supporting my new trackway I have illustrated, for the purposes of exemplification, a wooden base comprising a longitudinally extending member 10 having blocks 11 secured to the opposite ends thereof. A series of arms 12 radiate horizontally from each block 11 and carry at their outer ends vertical supports of varying heights and which will later be described.

The base members 10, 11 and 12 are all adapted to rest upon a floor or similar supporting surface. The trackway itself may be of any conventional type. I have illustrated a form of trackway which consists of a base or bed member 13 which is preferably of wood or other insulating material and carries thereon rails 14 which are of an electrical conducting material for the purpose of establishing an electrical circuit and supplying energy to a toy electric train of the usual type. In place of the construction shown the tracks may be supported upon a metallic base structure with a third rail insulated from the remaining structure and supplying the energizing current. Any desired and convenient type of toy trains, electrical or otherwise, may be used and the trackway adapted thereto.

My new trackway is endless and continuous in extent, that is, it traverses a complete closed circuit, but for the purposes of the present description and for describing the path thereof I shall begin at the central lowermost portion thereof.

At this point a portion 15 of trackway 13, 14 extends obliquely across the bar 10. This oblique track portion merges at each of its ends into a curvilinear portion 16, which in the instance illustrated is approximately an arc struck from the center of each block 11 and extending through approximately 270°, when both of the curvilinear portions merge into oblique portions 17 which are substantially adjacent each other and extend across the first mentioned oblique portion 10 at about right angles thereto.

During the course of the trackway from the first mentioned oblique portion to the two latter mentioned and co-planar oblique portions the trackway inclines gradually upwardly so that the two second named oblique portions are spaced above the first named oblique portion at a distance sufficient to permit a toy electric train to pass along the first mentioned oblique portion and beneath the two latter mentioned oblique portions. The two oblique portions 17 again merge into curvilinear portions 18, which in the instance illustrated approximate arcs struck from the blocks 11 and continue for about 270°, and merge into a common oblique track portion 19 which is, in the plan view, approximately coincident with the first named oblique track portion 15.

The curvilinear portions 18 also ascend gradually so that the oblique track portion 19 is spaced above the two adjacent intermediate track portions a distance sufficient to permit a toy electric train traversing either of the intermediate adjacent track portions 17 to pass beneath the upper track portion 19. Vertical supports 20 extend between the base of the track plate 13 and the base structures 10 and 12 at suitable intervals for supporting the trackway and the height of the several vertical supports 20 is graduated as required.

It will be noted that the curvatures of the lower track portions, that is, the track portions extending from the lowest level to the intermediate level, are of generally greater radius than the curvatures of the upper track portions, that is, those extending from the intermediate level to the topmost level. This difference in radius is preferably about the width of the trackway and is provided so that the toy train, when traveling from the lower to the intermediate level, will not be interfered with by the upper track portions or by their supports.

I prefer that my trackways be banked at curves so that there will be no danger of the toy train leaving the tracks owing to centrifugal

force. Such banking is illustrated at Fig. 3 which is a cross-sectional view taken at one of the curved portions. For greater structural stability I have shown, in my illustrated embodiment, reinforcing members 21 extending along the opposite sides of the railroad bed 13 in the vicinity of the central obliquely extending track portions 15, 17 and 19.

It will be seen that the oblique straightaway portions which are shown in the drawing and which have been described may be omitted entirely and the circular portions may be substantially complete so that they merge directly into each other, or the straightaway portions may all extend in the same direction, that is, at right angles to the member 10 as viewed in Fig. 1. The curvilinear portions have been shown as arcuate but it will be understood that these portions of the track may be of any suitable shape or configuration only so that they interconnect with the straightaway portions or with each other in the manner and at the levels described.

In operation the toy train beginning at the lowermost portion 15 of the trackway executes a figure 8. Midway in the execution of this figure 8 the train will be found at the intermediate level of track and upon completion of the figure 8 at the topmost level. The train continues from this point to execute a second figure 8, passing the intermediate level midway and again arriving at the lowermost level upon the completion of the second figure 8.

It has been found in practice that the toy railroad herein shown and described results in a train route which is pleasing to the eye and quite intriguing in that the path of the train does not readily photograph itself upon the mind of the observer. The exact modus operandi is not so clear from actual observation as pictorial delineation and verbal description may make it appear.

The path of movement of the train is graceful and to a large extent avoids the monotony incident to observation of the operation of a toy railroad train in a single level. The smoothness and grace of operation is further enhanced by the complete absence of switches or frogs and this latter feature results further in more quiet operation than is usually the case in devices of this class.

It will be understood that various modifications in the structure shown and described might be made without departing from the spirit or scope of the invention as defined in the appended claims.

55 I claim:

1. In a toy railroad, a trackway comprising two adjacent stretches of track, a track portion passing above and another track portion passing beneath said adjacent stretches of track, and curved track portions connecting the ends of said adjacent track portions to the upper and lower track portions to provide a continuous railroad.

2. In a toy railroad, a trackway comprising two adjacent stretches of track, a track portion passing above and another track portion passing beneath said adjacent stretches of track, curved track portions connecting the opposite ends of the upper track portion with one end of one of the adjacent track portions and the opposite end

of the other of the adjacent track portions respectively, and curved track portions connecting the opposite ends of the lower track portion with the ends of the adjacent track portions lying opposite their juncture with the first mentioned curved track portions to provide a continuous and endless trackway. 5

3. In a toy railroad, a trackway comprising two adjacent stretches of track, a track portion passing above and another track portion passing beneath said adjacent stretches of track, curved track portions connecting the opposite ends of the upper track portion with one end of one of the adjacent track portions and the opposite end of the other of the adjacent track portions respectively, and curved track portions connecting the opposite ends of the lower track portion with the ends of the adjacent track portions lying opposite their juncture with the first mentioned curved track portions to provide a continuous 10 and endless trackway, said second mentioned curved track portions lying substantially outside said first mentioned curved track portions. 20

4. In a toy railroad, a trackway comprising two adjacent stretches of track, a track portion passing above and another track portion passing beneath said adjacent stretches of track, arcuate track portions connecting the opposite ends of the upper track portion with one end of one of the adjacent track portions and the opposite end 30 of the other of the adjacent track portions respectively, and arcuate track portions connecting the opposite ends of the lower track portion with the ends of the adjacent track portions lying opposite their juncture with the first mentioned curved track portions. 35

5. In a toy railroad, a trackway comprising two adjacent stretches of track, a track portion passing above and another track portion passing beneath said adjacent stretches of track, arcuate track portions connecting the opposite ends of the upper track portion with one end of one of the adjacent track portions to the opposite end 40 of the other of the adjacent track portions respectively, and arcuate track portions connecting the opposite ends of the lower track portion with the ends of the adjacent track portions lying opposite their juncture with the first mentioned curved track portions. 45

6. In a toy railroad, a trackway comprising 55 four curvilinear track portions, one of said portions having one end in a given plane, said portion extending curvilinearly until the other end thereof lies adjacent said first end but in a plane thereabove, a second portion having one end 60 lying adjacent said second end of said first portion and in substantially the same plane therewith and having one of its ends connected with the first mentioned end of the first portion, the upper adjacent ends of both of said portions extending in two oppositely curved portions having their ends meeting in a plane above the two previously mentioned planes. 65
